Fig. 3

UNITED STATES PATENT OFFICE.

SAMUEL ACKERMAN, OF PHILADELPHIA, PENNSYLVANIA.

SANITARY COMBINED CUSPIDOR.

Application filed October 27, 1927. Serial No. 229,226.

This invention relates to a combined cuspidor and ash tray, and among the objects of the invention are to provide a novel, sanitary and convenient means of covering and uncovering the cuspidor and holding the cover in open position; to provide an ash tray, and a compartment for utensils for cleaning the cuspidor.

These objects, and other advantageous ends which will be described hereinafter, I attain in the following manner, reference being had to the accompanying drawings in which—

Figure 1 is a side elevation showing a device embodying the improvement,

Figure 2 is a front elevation of the device with the cover in an open position,

Figure 3 is a sectional view taken on the line 3—3 of Figure 2,

Figure 4 is a plan view,

Figure 5 is a sectional view taken on the line 5—5 of Figure 1,

Figure 6 is an enlarged sectional view taken on the line 6—6 of Figure 1.

Figure 7 is an enlarged fragmentary sectional elevation showing means for holding the cover in an open position, and

Figure 8 is a view similar to Figure 6, showing a modification.

In the drawings, 8 is a base in the form of a shallow box preferably enlarging upwardly with its back 9 higher than its sides and front. The box is provided with a rearwardly inclined partition 10, extending transversely between the sides with its upper edge flush with the upper edges of the sides and front.

A horizontal shelf 11 divides the box into an upper compartment 12 and a lower compartment 13. The upper compartment may serve as a cuspidor, but preferably serves as a receptacle for a removable container 14 which serves as the cuspidor. The front of the box is provided with an opening 15 below the shelf to receive a drawer 16 adapted to slide in the lower compartment.

A space is formed between back 9 and partition 10 and strips 17, having beveled ends 18, are secured to the sides and extend from the back 9 a short distance over partition 10, while their inner edges project in from the sides. A transverse strip 19 is secured to the upper edge of back 9 and side strips

17, and extends over the space above referred to, but leaves a space between its forward edge and partition 10.

A cover 20 is hinged near its rear end, to the top of partition 10, as indicated at 21, and the short end or heel extends into the space between partition 10 and back 9, while its longer end is adapted to close against the upper surfaces of the walls of compartment 12. A packing 22, of rubber or other material, to form a cushion, is secured to said surfaces and forms a tight joint between the bottom of the cover and the compartment when the cover is closed. The inner end of the cover is of reduced width, being cut-out at the corner as indicated at 23, to extend between side strips 17. The short end of the cover is provided with a concavity 24 and the transverse strip 19 has an opening 25 which registers with the concavity when the cover is closed.

A hollow upright or housing 26, preferably of rectangular cross section, is secured in a base 27 and this base is detachably secured to strip 19 over opening 25. A plunger 28, of rectangular cross section, is slidably mounted in the corresponding passage of upright 26 and has a reduced lower end 29. A bar 30 is pivoted at 31 to the reduced end 29 and has a reduced upper end 32 projecting beyond the pivot. The lower end of section 30 is beveled, as indicated at 33 and provided with a pin 34 extending into the concavity 24 and cover 20.

The upper end of upright 26 is tapered and a bracket 35 is bent in shape to fit thereon and is provided with a horizontal ring support 36 for an ash tray 37.

The drawer 16, affords a convenient receptacle for utensils, for cleaning the cuspidor, disinfectant, etc.

With the cover closed, the plunger will be in its high position with a major part of pivoted section 30 within the hollow upright or housing and its pin contacting with the cover. By pressing the plunger downward until the heel only of the pivoted section remains in the housing, the cover will be opened and, upon release of pressure upon the plunger, will close by its own weight. By pressing the plunger downward until the pivoted section is clear of the housing, the cover will be swung to open position and the pivoted section swung to an angle with

plunger part 28. Upon release of pressure on the plunger, the reduced beveled end 32 of the pivoted section 30 will engage the under surface of strip 19 and hold the cover in open position. The locking engagement of the pivoted section is sufficient to hold the cover open but may be released by a lifting pressure on the plunger.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A cuspidor comprising a receptacle, a hinged cover having a heel extension; a slidably mounted plunger having a pivoted section adapted to engage the heel of the cover,

and means for temporarily locking the cover in open position.

2. A cuspidor comprising a receptacle, a hinged cover having a heel extension; a slidably mounted plunger having a pivoted section adapted to engage and actuate the cover, the pivoted section having a projecting part adapted to engage a fixed part and hold the cover in open position.

3. A cuspidor comprising a box-like base, a transverse partition therein; a receptacle; a cover for the receptacle hinged to and extending beyond the partition; a hollow upright carried by the base; a plunger slidably in the upright and having a pivoted section adapted to engage the heel of the cover, the pivoted section having a rounded end extending upwardly from the pivot adapted to engage the plunger housing and hold the cover in open position, and to be disengaged by movement of the plunger.

In testimony whereof I have signed my name to this specification.

SAMUEL ACKERMAN.
